TAMPERPROOF SECONDARY CLOSURE

John E. Regan, Elmhurst, N. Y., assignor to Reynolds Metals Company, New York, N. Y., a corporation of Delaware

Application August 8, 1936, Serial No. 94,898

2 Claims. (Cl. 215—42)

This invention relates to tamper-proof seals of the type which when placed on the bottle or other container cannot be wholly removed therefrom without breaking the bottle or container, or destroying a portion of the seal, and also relates to a particular form of container neck especially adapted for use with such a seal.

An object of this invention is the provision of a tamper-proof seal adapted to form a secondary closure upon a capped or stoppered bottle, which seal is formed in two parts: a top part which is detached or torn away when the bottle or container is initially opened and a bottle or band portion which is relatively permanently placed upon the bottle or container preferably by being spun into a grooved recess of a container neck.

A further object of this invention is to so form the upper cap portion and the lower or band portion integrally and in such a manner that the cap portion is easily separated therefrom and so that there will be no exposed jagged or raw edges which might cut the hands of users of the containers, by means of forming slits and relatively weak bridge members between the upper portion and the band portion within a grooved recess.

A further object of my invention is to so form the bottle or container neck of a portion of a seal of the class described that it may be readily spun in position upon such neck and will remain in fixed relation in respect thereto, the combination of container neck, cap and secondary closure being economical to manufacture and attractive and efficient in design.

These and various other objects and advantages will be readily understood from the following description taken in connection with the accompanying drawing of a preferred embodiment of the invention in which however modifications may be made without departing from the scope 40 of the appended claims.

In the drawing—

Fig. 1 is a perspective view of a secondary closure, or seal, which embodies my invention;

Fig. 2 is a vertical section taken on the line 45 2—2 of Fig. 1;

Fig. 3 is a plan view of the seal illustrated in Fig. 1;

Fig. 4 is a vertical cross section of a container neck, preferred form of cap and secondary closure embodying my invention;

Fig. 5 is a horizontal cross section taken on the line 5—5 of Fig. 4; and

Fig. 6 is a side elevation of the device illustrated in Fig. 4 with the top portion of the seal

detached from the band portion, said top portion being illustrated by a vertical section.

Referring to the drawing, a bottle neck 10 is provided with a flat topped lug cap 11, which latter is secured to the bottle neck by glass projections 12. Instead of lug cap 11 it is obvious that various classes of caps or stoppers could be efficiently employed. A secondary closure or seal 13 comprised of an upper cap portion 14 and a lower band portion 15 is positioned above the cap 10 in a manner adapted to encompass the cap and a portion of the bottle neck 10, and is secured to the bottle neck 10 by having a portion of the band 15 spun into annular groove 16 of the bottle neck 10. Annular groove 16 formed in the bottle neck 15 5 has an upper shouldered portion 17 formed with corrugations 18 against which the band 15 is spun; the groove 16 has a lower hollowed out portion indicated as 19, which hollowed out portion permits the spinning without interference of 20 the lower edge identified as 19—A of band 15. The upper part 20 of band 15 is folded back on itself to provide an annular groove indicated as 21 between upper cap 14 and band 20. Upper cap 14 may have its skirt portion indicated as 22 25 formed with corrugations 23. Upper cap 14 and the band 15 are formed integrally so that one may be easily detached from the other and are slotted one from the other by circular slits 24 (best seen in Fig. 3) which are formed at the 30 annular groove 21 but narrow bridge portions indicated as 25 are left to connect the two portions of the seal. It will be noted that the bridge portions or members 25 are located at the bottom of groove 21 whereby when the cap portion of 35 the seal is detached by twisting, any jagged sheered edges of bridge members 25 are shielded from the hands of users of the container by the upper folded-back part 20 of the band 15. Band 15 is intended for more or less permanent engagement upon the bottle neck and is only removed by the manufacturer or filling companies 40 in the event of refilling the container.

It is obvious that a seal of the type described herein may be made of various types and thicknesses of sheet metal, but I have found that annealed sheet aluminum .006" thick may be formed into a seal satisfactorily.

What I claim is:

1. A tamper-proof secondary bottle closure of 50 circular cross section formed of thin sheet metal from an integral blank comprising a band portion adapted to be mounted relatively permanently upon a container neck with a groove by having a lower portion spun into said groove, 55

said band portion having substantially a vertical side wall terminating in an internal vertical turnback, a cap portion of narrower circular cross section than said band portion adapted to overlie a primary closure having a vertical side wall and extending downwardly inside said turnback, and rupturable connective means joining the lower edge of the side wall of the cap portion to the

edge of said turnback, whereby when the cap portion is removed, the turnback of the band portion shields ruptured edges of said rupturable connective means.

2. A closure as defined in claim 1 wherein said rupturable connective means comprise narrow bridge members.

JOHN E. REGAN.
